(57) CLAIM

The ornamental design for a support trim rail for panel wall system, as shown and described.

DESCRIPTION

FIG. 1 is a top, front and side perspective view of a support trim rail for panel wall system showing my new design, the center portion of the figure is broken away for purposes of maintaining the proper scale;

FIG. 2 is a front elevational view thereof;

FIG. 3 is a right side elevational view thereof, the left side elevational view being a mirror image;

FIG. 4 is a top plan view thereof, the bottom plan view being identical; and

FIG. 5 is a rear elevational view thereof; and,

FIG. 6 is a bottom plan view thereof.
